CLAIM

The ornamental design for a plumbing fitting, substantially as shown and described.

DESCRIPTION

FIG. 1 is a top isometric view of a plumbing fitting, showing my new design.

FIG. 2 is a bottom isometric view thereof.

FIG. 3 is a top plan view thereof.

FIG. 4 is a bottom plan view thereof.

FIG. 5 is a front elevational view thereof, the back, right, and left elevational views are the same as the front elevational view; and,

FIG. 6 is a cross sectional view of the plumbing fitting along the line 6-6 of FIG. 3.

Stippling and tangent lines shown in the drawings are intended to represent the three-dimensional contour of the design, and are not intended to indicate surface decoration. The broken lines depict portions of the article that form no part of the claim.
